UNITED STATES PATENT OFFICE.

MARCEL BAZILLE, OF ANGERS, FRANCE.

SAFETY-LOCK FOR CAR-DOORS.

1,127,721.

Specification of Letters Patent. Patented Feb. 9, 1915.

Application filed April 10, 1912. Serial No. 689,831.

To all whom it may concern:

Be it known that I, MARCEL BAZILLE, a citizen of the Republic of France, residing at 13 Rue Cubain, Angers, Maine-et-Loire, in the Republic of France, locksmith, have invented certain new and useful Improvements in Safety-Locks for Car-Doors, of which the following is a specification.

This invention relates to safety locks for car-doors, and has for its object to so construct a lock of this character that it will prevent children from opening the door from the inside. For this purpose, the lock is combined with a locking device which normally locks the inner handle or one of its members and which only releases the handle when an unlocking member located in the carriage at a height which cannot be reached by children has been operated. Furthermore, such lock is so fitted as to allow of the door being easily opened from the outside as well as from the inside by travelers, while not permitting the door to be accidentally opened by vibration, jarring, or the like. The safety closure is obtained solely by the closing motion of the door and the proper position of the closing members can easily be verified from the inside as well as from the outside.

One embodiment of my invention is shown, by way of example in the accompanying drawings, in which:

Figure 1 is an elevation of a part of the inside of a car-door provided with the lock according to this invention. Fig. 2 is a detail vertical section through the plane of the lock spindle. Fig. 3 is an elevation of the interior of the lock, the inner plate of the lock being removed, and Fig. 4 is a vertical section of a locking device located at the outside of the door.

Such lock comprises a plate 1 squarely bent to fit the inner angle of the door 2; on such plate is guided an inwardly curved latch 3 which is pushed outwardly by the spring 4. Such latch can be pushed inwardly either by the member 5 of the outer handle 6 or by a two arm lever 7 which is connected with the spindle 8 of the inner handle 9. The spindle 8 has a projection 10 in the shape of a nose which can be locked by an automatic fastening bolt consisting of a vertical rod 11 slideable in a groove provided in the door, above the lock, which is closed by a plate 12. The lower end of such rod is beveled and guided between two lugs 13 integral with the

plate 1 and located close to the path of the projection 10 so that the portion of the rod which projects beyond the lugs 13 is very small and the rod is not liable to be bent by the projection 10 in case pressure should be brought to bear on the handle 9, before raising the rod 11. The upper end of the latter is pivoted to one of the arms of a bell crank lever 14 the opposite arm of which is pivoted to a push button 15, protruding a little beyond the inner face of the door. Under the action of gravitation, the rod 11 falls automatically down in front of the projection 10 and prevents the rotation of the inner handle 9, so that the door cannot be opened from the inside unless the button 15 be pressed by one hand to raise the rod 11, while the other hand is acting on the handle 9.

16 designates a spring which acts on the member 8 in such a manner as to raise the handle 9 when left to itself and 17 indicates a pin integral with the latch and serving to maintain the member 5 against the heel of the latch.

The position of the latch is indicated at the outside by the handle 6 and at the inside by an index 18 integral with the spindle of such handle.

In order to prevent the door from being opened from the outside, the lock is provided with a locking device called a "service stopper," comprising a cam 19 secured on the spindle of the outer handle 6 and a rotary abutment 20 which, on being set up straight as shown in the drawing, engages in a corresponding slot in the cam, so as to prevent any rotation of the latter and hence the opening of the lock. Such abutment has a square projection 21 which allows of it being turned from the outside by means of a suitable key. Its rotation is limited in both directions by stopping members 22, 23. When it is against the stopping member 23, it leaves a free passage to the cam 19 and allows the lock to operate.

Claims.

1. The combination with a door, of a lock having a latch, inner and outer handles for independently operating said latch, a knob spindle on which said inner handle is fixed a projection on said knob spindle, a rod movable on the door and operable to engage said projection when the inner handle is in latch projecting position, a bell crank lever connected with said rod, and a lever actu-

- ating device disposed at a point remote from said lock.
2. The combination with a door, of a lock having a latch, inner and outer handles for independently operating said latch, a knob spindle on which said inner handle is fixed a projection on said knob spindle, a rod movable on the door and operable to engage said projection when the inner handle is in latch projecting position, a bell crank lever connected with said rod, and a push button connected with said lever and disposed at a point remote from said lock.
3. The combination with a door, of a lock having a latch, inner and outer handles for independently operating said latch, means for locking said inner handle in latch pro-
- jecting position, releasing means for said locking means located in a plane above the lock, a locking device for the outer handle comprising a cam secured to the outer handle, a rotary abutment positioned to be engaged by said cam when said outer handle is in closed position, and key actuated means on said abutment for releasing said outer handle.
- In testimony, that I claim the foregoing as my invention I have signed my name in presence of two subscribing witnesses.

MARCEL BAZILLE.
